EASEL POSTER

Battista Salussolia, Wood Ridge, N. J., assignor
to Sweeney Lithograph Company, Inc., Belle-
ville, N. J., a corporation of New York

Application November 17, 1943, Serial No. 510,839

6 Claims. (Cl. 40—125)

The invention herein disclosed relates to flexible posters of the easel type and special objects of the invention are to provide an easel construction for such posters, which will be particularly simple and inexpensive, easily set up, foldable into small compass and made up practically entirely of readily obtainable material, such as commercial wooden strips or rods.

These and other desirable objects are attained by the novel features of construction, combinations and relation of parts, as hereinafter set forth, illustrated by way of example in the accompanying drawing and broadly covered in the claims.

Fig. 1 in the drawing referred to is a rear perspective view of an easel poster constructed in accordance with and embodying features of the invention.

Fig. 2 is a view in perspective and side elevation showing the poster and easel rolled and folded as for transportation or storing.

Fig. 3 is an enlarged broken part sectional detail illustrating the hinge and detent construction for the supporting rod member of the combination.

Fig. 4 is a side view illustrating a modified form of the invention.

In the several views, a flexible roll-up type of poster is indicated at 5, having upper and lower edge strips 6 and 7. These edge strips are shown as having rearwardly faced openings 8 and 9, for reception of the rods completing the easel structure.

10 indicates a base rod having its forward end engaged in the opening in the bottom edge strip and 11 designates a supporting rod having its lower end seated on the base rod and its upper end engaged in supporting relation in the opening 8 in the upper edge strip.

The attachment of the supporting rod to the base rod is conveniently effected by providing a seating 12, in the rearwardly extended end portion of the base rod for reception of the lower end of the supporting rod.

For making the several connections thus far described, the ends of the rods may be turned down as dowels to enter corresponding openings in the companion members.

The supporting member is braced in upstanding forwardly angled relation by an inclined brace strip 13, which may be of thin, flexible and more or less resilient material and which is wedged in such bracing and supported relation across the angle between the connected ends of the rods.

In the form of the invention shown in Figs. 1 and 2, the brace strip 13, is shown pivoted at 14, on the upper face of the base rod 10, at one end and as bendable upward at its free end into interlocked engagement in a notch 15, in the upright rod.

In the modified form of the invention shown in Fig. 4, the thin flexible brace strip 13, is anchored or fulcrumed at its lower end by seating in notches 16, in the upper face of the brace strip and is caught to the upright at its upper end by engaging in one of the notches 17 in that member.

In both constructions, the thin strut or thrust piece 13, when wedged in place, forms a spring, tensioning the angularly related rods apart, thus to hold the flexible easel stretched taut in the manner illustrated.

In the first form of the invention, the strut 20 piece remains attached to and forms a permanent part of the brace rod, whereas in the second form, the bendable strut is a thin flat piece separate from other parts and adapted to be packed in any convenient manner flat against the other parts.

All the parts mentioned, except the poster itself, may be made of light inexpensive wooden strip or rod material.

To provide greater resiliency, reduce weight and attain a more compact bundle for shipment, the upright support may be made in two parts, a lower relatively rigid section 18, and an upper lighter and thinner section 19, hingedly connected together at 20. These two parts are shown as yieldingly held in their extended relation by a round head abutment 21, seated in the upper portion of the more rigid member, arranged to engage a seat 22, in the opposing face of the lighter, more resilient member. The yielding nature of the upper lighter strip enables this simple combination to provide a satisfactory detent for firmly retaining the foldable upright in the extended relation indicated in Figs. 1, 3 and 4.

46 What is claimed is:

1. A flexible poster having upper and lower edge strips at the top and bottom of the same, said edge strips having rearwardly faced openings therein, rearwardly and upwardly projecting supporting rods having ends engaged in said openings and having the opposite ends of the same connected in relatively angled relation, a thrust transmitting brace strip wedged in compression across the angle between said connected ends of the supporting rods, said brace strip being of

thin flexible material to bend when wedged across the connected end portions of the rods and being pivotally mounted on the upper face of the rod which is engaged with the bottom edge strip on a substantially vertical axis and bendable up out of the plane of that rod into engagement with the inner face of the upwardly projecting supporting rod.

2. A flexible poster having upper and lower edge strips with openings in the back of the same, a bottom rod engaged in the opening in the lower edge strip, a supporting rod comprising a lower relatively rigid section having its lower end connected with the rearward end of said first rod and an upper section of thinner, flexible material hinged to the upper end of said relatively rigid section, the upper end of said hinged flexible section being engaged in the opening in the upper edge strip and a brace engaged across the angle between the connected portions of the lower rod and said relatively rigid lower section of the support.

3. A flexible poster having upper and lower edge strips with openings in the back of the same, a bottom rod engaged in the opening in the lower edge strip, a supporting rod comprising a lower relatively rigid section having its lower end connected with the rearward end of said first rod and an upper section of thinner, flexible material hinged to the upper end of said relatively rigid section, the upper end of said hinged flexible section being engaged in the opening in the upper edge strip, a brace engaged across the angle between the connected portions of the lower rod and said relatively rigid lower section of the support and cooperating detent means on said hingedly connected upper and lower sections for releasably retaining the same in extended relation.

4. A flexible poster having edge strips at the upper and lower ends of the same, a rearwardly extending base rod connected with the lower edge strip, a supporting rod having its lower end seated on the rearwardly extending portion of said base rod and its upper end in supporting engagement with the upper edge strip and a flexible springy brace strip disposed in inclined relation across

the angle between the connected portions of said base and supporting rods and in thrusting engagement at its opposite ends with said base rod and with said supporting rod, at least one of said rods having one or more notches for reception of one end of said brace strip and means for securing the other end of said brace strip in non-slipping engagement with the face of the other supporting rod which is opposite said notch or notches and whereby said brace strip may be sprung into yielding thrust transmitting engagement across said angle between the rods described.

5. An easel poster, comprising a flexible poster having upper and lower edge strips, a foldable support having hingedly connected upper and lower sections, the lower section being of heavier more rigid material than the upper section, a protruding detent plug seated in the heavier lower section in opposition to the hingedly connected upper section, said upper section having a seat engagable over the protruding portion of said plug for retaining the two hingedly connected sections in extended relation, said upper section having a supporting engagement with the upper edge strip and a base rod connected with the lower edge strip and having a supporting connection with the lower end of said heavier more rigid section of the support.

6. An easel poster, comprising a flexible poster having upper and lower edge strips, a foldable support having hingedly connected upper and lower sections, the lower section being of heavier more rigid material than the upper section, a protruding detent plug seated in the heavier lower section in opposition to the hingedly connected upper section, said upper section having a seat engagable over the protruding portion of said plug for retaining the two hingedly connected sections in extended relation, said upper section having a supporting engagement with the upper edge strip, a base rod connected with the lower edge strip and having a supporting connection with the lower end of said heavier more rigid section of the support.

BATTISTA SALUSSOLIA.
